Primary Examiner — Mark A Goodwin(74) *Attorney, Agent, or Firm* — Westman, Champlin & Koehler, P.A.; Amanda M. Prose(57) **CLAIM**

The ornamental design for a plow assembly, as shown and described.

DESCRIPTION

FIG. 1 is a perspective view of the plow assembly;

FIG. 2 is a front elevational view thereof;

FIG. 3 is a rear elevational view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the plow assembly that form no part of the claimed design. The dash-dot broken lines define the bounds of the claimed design and form no part thereof.

1 Claim, 7 Drawing Sheets(56)
